UNITED STATES PATENT OFFICE.

HERBERT GREGORY, OF CONCORD, CALIFORNIA, ASSIGNOR TO NATIONAL LEAD COMPANY OF CALIFORNIA, A CORPORATION OF CALIFORNIA.

PROCESS FOR THE PRODUCTION OF WHITE LEAD.

Application filed April 18, 1921. Serial No. 462,222.

To all whom it may concern:

Be it known that I, HERBERT GREGORY, a citizen of the United States, residing at Concord, in the county of Contra Costa, State 5 of California, have invented a new and useful Process for the Production of White Lead, of which the following is a specification in such full and clear terms as will enable those skilled in the art to construct and 10 use the same.

This invention relates to a process for the production of white lead and its object is to simplify the oxidation of the lead while preserving the beneficial result attained by the 15 old style method of treatment.

It will be understood by those skilled in the art that in the production of white lead it is common to surround a series of pots containing the lead and the reagents necessary with material such as wet straw, tan bark or other decomposing materials which will produce sufficient carbon dioxide to complete the process and to allow the treatment to continue for a period of from three to 25 four months at the end of which time it will be found that a large per cent of the metallic lead has changed into white lead substantially of the formula $2\text{PbCO}_3\text{Pb}(\text{OH})_2$.

The disadvantage of the foregoing procedure is that unless great care is taken to prevent particles of the material used to produce the CO_2 and to heat the stack, from getting into the pots white lead will be found to be specked with the material used to cover 35 the pots and in addition where the stacks are made with a thick layer of tan bark or other decomposing material between each layer of pots that much unnecessary space is wasted.

With the present invention artificial heat 40 and moisture are supplied to assist in raising the temperature to the desired point and this heat and moisture may be supplied as long as is deemed necessary to maintain the stack at any given temperature. The control of 45 the temperature and the control of evaporation of the reagents used is effected by a suitable flue extending through the stack.

Other objects of the invention will appear as the description proceeds.

50 An embodiment of the invention is shown in the accompanying drawings in which the same reference numeral is applied to the same portion throughout but I am aware that there may be modifications thereof.

Fig. 1 is a perspective view of a series of 55 stacks used to carry out this process.

Fig. 2 is a vertical sectional view of one of the stacks.

Fig. 3 is a plan view of portions of the stacks.

A stack house consists of a plurality of 60 square chambers supported by posts 1 to 4 inclusive in such numbers as the number of stacks requires there being one complete series of posts at the ends of the stack house 65 and at the junction of each chamber with each other chamber.

The stack house is provided with rafters 5 for the support of the roof and the ventilating house 6 and there are overhead tracks 7 70 and 8 for handling the material to be placed in the several stacks.

Inside the outer walls 9 and 10 of the stack house there are 8 posts 11 to 18 inclusive 75 which posts support a plurality of louvers 19, said louvers are so inclined that the decomposing material placed between the louvers and the outer walls 9 and 10 of the stack house as to prevent said materials from falling 80 inside the stack.

The metallic lead in buckles or other finely divided form is placed within a plurality of suitable containers 20, said pots or containers being placed inside the stack house and upon each layer of pots there are placed a plurality of boards 21 for the support of the next upper layer of pots. At the top there is placed a tight layer of boards 22 which prevents any material from passing through into the inside of the stack. The louvers are 90 placed within the stack house about two feet six inches distant from the outer walls thereof and the space between the outer walls of the stack and the louvers is completely filled with the tan bark or other material used. 95 When the stack has been filled with the pots they are covered with the boards and a layer of about two feet of tan bark, straw or other decomposing material.

Adjacent each of the inner posts 11 to 100 18 of each stack are a plurality of perforated steam pipes 25 and 26 all of said pipes being connected by means of the pipes 28 to 32 inclusive to a main steam supply pipe 33. In order to ventilate the interior of the stack 105 a flue 40 is placed in the center. This flue has holes in its sides and is open at the top. A cover 41 is placed on the top of the flue

and it is shifted as may be necessary to increase or diminish the quantity of steam escaping from the flue. The several stacks are spaced apart at the center and there is 5 a walkway 36 leading down the center of the building, such walkway being reached by a stairway 37.

The operation of the process is as follows: Assuming the stack to be ready for charging, the space between the louvers of the inner stack and the outer walls is filled with tan bark, straw or other decomposing material. Thereupon the layers of containers or pots, in which containers the lead buckles 10 and reagents are placed, are then placed within the inner stack in layers. Boards are laid upon each layer of pots to distribute the weight of the next layer of pots more evenly, and the stack is completely filled. 15 Thereupon a tight cover is put across the top layer of pots and the stack is then completely covered with a layer of about two feet thick of the material used to fill the stack at the sides. Thereupon the mass is 20 heated by the live steam escaping from the several pipes adjacent the inside posts and the stack is heated to such a temperature as has been ascertained by previous experience will produce the quickest corrosion of 25 the lead and this temperature will be maintained as long as is deemed necessary to accomplish the desired results. Ordinarily it will be found that white lead may be produced by the process herein described 30 in from 30 to 60 days less than the time required by the old process where each individual pot is covered over with tan bark or straw, and in addition to the above there is no danger of small particles of tan bark 35 getting into the several pots since the upper layer of material can be completely cleaned off before any of the pots are opened. It will also be seen that there is no danger of the pots being broken or disturbed by the 40 sinking of the mass of material upon which they are piled, and the economy of space is 45 greatly increased.

What I claim is as follows, but modifica-

tions may be made in the above particularly described form of the invention within the 50 purview thereof.

1. A process of producing white lead which consists in placing a plurality of receptacles containing lead in a suitable form for corrosion with the necessary reagents 55 in an enclosure, covering the mass of containers with a layer of decomposing materials for the purpose of producing carbon dioxide, heating the mass of said materials with steam to the temperature of most effective chemical action and maintaining such temperature until the lead has been corroded.

2. A process of producing white lead which consists in placing a plurality of receptacles 60 containing lead in a suitable form for corrosion together with the necessary reagents in a suitable enclosure, covering said enclosure and the mass of receptacles with a complete layer of decomposing materials for 70 the purpose of producing heat and carbon dioxide, heating the mass with steam to the temperature of most effective chemical action and maintaining such temperature together with the necessary moisture until the 75 lead has been sufficiently corroded.

3. A process of producing white lead which consists in placing a plurality of layers of receptacles containing lead in a suitable form for corrosion with the desired 80 reagents in an enclosure, covering the mass of receptacles with a single layer of decomposing materials for the purpose of producing carbon dioxide, heating the mass of decomposing materials with wet steam to 85 the temperature of most effective chemical action, maintaining such temperature until the lead has been sufficiently corroded and at the same time continuing the supply of moisture from the steam pipes to prevent 90 undue evaporation from the receptacles.

In testimony whereof I have hereunto set my hand this 29th day of March, A. D. 1921.

HERBERT GREGORY.
